ELECTRIC LAMP HOLDER

Richard T. Kennedy, Oak Lawn, and James L. Hvale,
Chicago, Ill., assignors to Bell Electric Company,
Chicago, Ill.

Filed Oct. 29, 1973, Ser. No. 410,739

Term of patent 14 years

Int. Cl. D26—03
U.S. Cl. D48—20 K

FIG. 1

FIG. 3

FIG. 2

FIG. 5

FIG. 4

FIG. 6

FIG. 7

FIG. 8

FIG. 9

FIG. 10

FIG. 11

FIG. 12

FIG. 1 is a perspective view of an electric lamp holder showing our new design;

FIG. 2 is a rear elevational view thereof;

FIG. 3 is a side elevational view thereof;

FIG. 4 is an elevational view of the side opposite the side shown in FIG. 3;

FIG. 5 is a front elevational view thereof;

FIG. 6 is a top view thereof;

FIG. 7 is a bottom view thereof;

FIG. 8 is a perspective view of another form of our new design wherein the lamp holder includes a hooded lens shield concentric with the lamp holder as shown in FIG. 1 through FIG. 7;

FIG. 9 is a perspective view of yet another form of our new design wherein the lamp holder includes an extender ring concentric with the lamp holder as shown in FIG. 1 through FIG. 7;

FIG. 10 is a perspective view of yet another form of our new design wherein the lamp holder includes an extender ring and a hooded lens shield, the extender ring and lens shield being concentric with the lamp holder as shown in FIG. 1 through FIG. 7;

FIG. 11 is a perspective view of yet another form of our new design wherein the lamp holder includes two extender rings concentric with each other and with the lamp holder; and

FIG. 12 is a perspective view of another form of our new design wherein the lamp holder includes two extender rings concentric with the lamp holder as well as a hooded lens shield also concentric with the lamp holder.

The support rod is broken away to indicate indeterminate length.

We claim:

The ornamental design for an electric lamp holder, substantially as shown and described.
